(57) **CLAIM**

The ornamental design for a display screen or pair of display screens with transitional graphical user interface, as shown and described.

DESCRIPTION

FIG. 1 is a pair of display screens with transitional graphical user interface showing our new design according to a first embodiment;

FIG. 2 is the second image thereof;

FIG. 3 is the third image thereof;

FIG. 4 is a display screen with transitional graphical user interface showing our new design according to a second embodiment;

FIG. 5 is the second image thereof; and,

FIG. 6 is the third image thereof.

The outermost broken line rectangles in FIGS. 1-3, shown in the upper and lower portion of each figure, illustrate two separate display screens and form no part of the claimed design. The outermost broken line rectangle in FIGS. 4-6 illustrates a display screen and forms no part of the claimed design. The remaining broken lines in the figures illustrate portions of the graphical user interface that form no part of the claimed design.

The appearance of the transitional image sequentially transitions between the images shown in FIGS. 1-3 and 4-6, respectively. The process or period in which one image transitions into another image forms no part of the claimed design.
